UNITED STATES PATENT OFFICE.

GEORGE E. PARKER, OF AMSTERDAM, NEW YORK.

MATCH-SAFE.

No. 918,085.

Specification of Letters Patent. Patented April 13, 1909.

Application filed July 29, 1908. Serial No. 445,876.

To all whom it may concern:

Be it known that I, GEORGE E. PARKER, a citizen of the United States, residing at Amsterdam, county of Montgomery, and State of New York, have invented certain new and useful Improvements in Match-Safes, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a front elevation of the improved match-safe mounted upon a stationary upright. Fig. 2 is a central, vertical, cross-section of the same taken on the broken line 2—2 in Fig. 1. Fig. 3 is a cross-section of the tilting bottom of the match-receptacle taken on the broken line 3—3 in Fig. 2. Fig. 4 is a central, vertical, cross-section, similar to that shown in Fig. 2, showing a movement of the parts. Fig. 5 is a horizontal section taken on the broken line 5—5 in Fig. 1, viewed in the direction of the arrow. Fig. 6 is a top plan view of the match-receptacle detached.

The object of the invention is to provide a match-safe with means whereby matches may be taken therefrom, one only at a time. The invention consists in providing a match-receptacle with a tilting bottom and pendulous front and controlling stops, whereby the movements of the front and bottom act as an escapement for delivering the matches, one at a time, to a position located exteriorly of the receptacle; and means for yieldingly maintaining the parts in their normal position for retaining the matches within the receptacle, as will hereinafter be more fully described and subsequently pointed out in the claims.

The match-receptacle, 1, comprises a stationary back wall, 2, adapted to be detachably secured to a support, 3, by means of a screw, 4, the side walls, 5, both preferably made integral with the back wall, a cover, bottom and front. The pendulous front, 6, is secured to the side walls by pivot, 7, the tilting bottom, 8, secured to the side walls by means of the pivot, 9, and the cover, 10, secured to the side walls by the same pivot

which supports the pendulous front. The pivot, 7, passes through the hinged sections, 12, which are integral with the front, 6, and through the hinged section, 13, integral with the cover, as seen in Fig. 1.

The edge of the front which was left remaining when the hinged sections, 12, were bent into form, is bent inwardly to form the support, 14, as shown in Figs. 2 and 4, and indicated by dotted lines in Fig. 6. The weight of the cover resting upon this support is sufficient to force the pendulous front outwardly. As a means for limiting the pendulous movements of the front, stops, 16, are secured thereto, adapted to engage with the coacting stops, 17, fixed to the side walls respectively. The inward pendulous movement of the front is limited by the engagement of stop, 16, with stop, 17, and the outward pendulous movement of the front is limited by the engagement of the front with the stops, 17, as seen in Fig. 5. As a means for limiting the tilting movements of the bottom, stops, 20, project from the side walls in the position to engage the front end of the bottom, and limit the downward tilting movement of the front edge of the bottom, as seen in Fig. 4. The upward tilting movement of the front edge of the bottom is limited by contact of the inner edge, 21, of the bottom with the back wall of the receptacle or case, as seen in Fig. 2.

The operation of the device is as follows: The hinged cover is swung open and a supply of matches, 25, placed in the receptacle or case. The matches first placed in the receptacle slide down the inclined tilting bottom to the position shown in Fig. 2, one match falling into the groove, 26, which runs along the lower front edge of the bottom, and another match resting on top of the one in the groove, the remaining matches being held in position by the inclined bottom and side and back walls, and the pendulous front, practically as shown. The front now occupies its outward position, being held against further outward movement by the stops, 17, thereby preventing the escape of the matches from the receptacle. To remove the lower match from the groove in the bottom it is only necessary to press the pendulous front inwardly until its stops, 16, strike the outer side of the stops, 17, thereby forcing the matches up the inclined bottom, and tilting the bottom by depressing its front edge, as shown in Fig. 4, wherein the

front portion of the bottom is shown in engagement with the stop, 20, and the lower edge of the front in engagement with the contiguous matches within the receptacle, in 5 a position to hold them upon the inclined bottom, and prevent their escape from the receptacle, at the same time leaving the match which was in the groove of the bottom free to be grasped between the thumb 10 and finger, and removed from its groove and from the receptacle. When the match is removed, and the thumb or finger withdrawn from the pendulous front, the weight of the cover will restore the front to its normal position, and the weight of the bottom will also 15 restore the bottom to its normal position, all the parts occupying the position shown in Fig. 2, the lowermost match falling into the groove in the tilting bottom, as shown, 20 whereupon the operation can be repeated until all the matches are withdrawn, one at a time, from the receptacle. When the pendulous front is pushed inward so as to engage the match resting upon the match in the 25 groove, it not only forces such match up the inclined tilting bottom, but serves to tilt the bottom by pressing downwardly through the match upon the front portion of the bottom.

By providing the lower part of the pendulous front with an inwardly projecting rib, 28, extending lengthwise of the matches, as shown in Fig. 4; the match which rested on top of the match in the groove of the bottom is forced back up the inclined bottom, and 35 locked in position thereon, while the matches above it are forced still farther back, thereby permitting the match which rested upon the match in the groove, as shown in Fig. 2, to drop down into the groove when the match 40 therein is removed therefrom, and the next match above to fall forward to a resting position upon the match so placed in the groove, as seen in Fig. 2. As a means for raising the heads of the matches from the surface of the 45 inclined bottom, two projecting corrugations, 30, are formed in the bottom, as seen in Figs. 2, 3 and 4. Similar projecting corrugations, 31, are formed in the back wall of the receptacle to prevent the heads of the 50 matches engaging with such wall. The head 34, of the match resting in the groove of the tilting bottom is shown in Fig. 1 partly in dotted lines. The cover may be provided with a small slot, 35, through which the stem 55 of a match may be inserted to open the cover. When desired, the part, 36, may be removed from the lower side of the tilting bottom, and the stop, 20, projected upward sufficiently to engage the main body part of the inclined 60 bottom, the bottom being then made of a

single piece of sheet metal stamped to the desired form. The groove wall of the inclined bottom is cut away at the middle of its front edge, as seen in Fig. 1, and the middle part of the lower outwardly projecting edge of the pendulous front is also cut away opposite the cut in the bottom groove, as shown at, 39, in Fig. 5, to permit free access to the match in the bottom groove when the front is pushed in, as shown in Fig. 4.

What I claim as new and desire to secure by Letters Patent is—

1. A match-safe comprising a match-receptacle having a tilting bottom pivotally supported intermediately of its front and rear edges; a pendulous front, a hinged cover, and stops for controlling in opposite directions, respectively, the tilting and pendulous movements of the bottom and front, whereby the neighboring edges of the front and bottom 75 form an escapement for releasing matches, one at a time, from the case.

2. A match-safe comprising a match-receptacle having a tilting bottom pivotally supported intermediately of its front and rear edges provided along its front edge with a match-receiving groove, a pendulous front having along its lower edge a convex surface adapted to engage a match resting upon the match in the front groove in the bottom, 80 means for normally maintaining the front at the outward limit of its pendulous movement, and stops for controlling in opposite directions, respectively the tilting and pendulous movements of the front and bottom. 85

3. A match-safe comprising a match-receptacle, having a tilting bottom provided with a match-groove along its front edge, adapted to receive a single match, a pendulous front having its lower edge adapted to override a match contained in the bottom-groove, and engage the match resting upon the match in the groove, and stops for limiting in opposite directions, respectively, the pendulous and tilting movements of the 100 front and bottom.

4. A match-safe comprising a match-receptacle, having a tilting bottom, a pendulous front, a hinged cover, adapted to bear by force of gravity against the front and normally maintain the same at its outward limit of movement, and stops for controlling the movements of the front and bottom, respectively. 110

In testimony whereof, I have hereunto set 115 my hand this 25th day of July, 1908.

GEO. E. PARKER.
